(57) **CLAIM**

We claim the ornamental design for an electronic module housing, as shown and described.

DESCRIPTION

FIG. 1 is a front, right side perspective view of an electronic module housing showing the design;

FIG. 2 is a top plan view of the electronic module housing of FIG. 1;

FIG. 3 is a front elevation view of the electronic module housing of FIG. 1;

FIG. 4 is a bottom view of the electronic module housing of FIG. 1;

FIG. 5 is a rear elevation view of the electronic module housing of FIG. 1;

FIG. 6 is a left side elevation view of the electronic module housing of FIG. 1; and,

FIG. 7 is a right side elevation view of the electronic module housing of FIG. 1.

The broken lines shown represent unclaimed subject matter and form no part of the claimed design. The portion of the

(Continued)

article that is not illustrated in the Figures is not claimed. The relatively light and thin shade lines show contour and not surface decoration.
